(57) **CLAIM**

The ornamental design for a lid for tumbler, as shown and described.

DESCRIPTION

FIG. 1 is a perspective view of a lid for tumbler, showing my new design.

FIG. 2 is a front, elevation view thereof.

FIG. 3 is a rear, elevation view thereof.

FIG. 4 is a left side, elevation view thereof.

FIG. 5 is a right side, elevation view thereof.

FIG. 6 is a top, plan view thereof; and,

FIG. 7 is a bottom, plan view thereof.

The broken lines in FIG. 7 illustrate a portion of the lid for tumbler that does not form a part of the claimed design.
